[57] **CLAIM**

The ornamental design for a combined cab and body for an earth-moving and handling machine, substantially as shown and described.

DESCRIPTION

FIG. 1 is a right side elevational view of a combined cab and body for an earth-moving and handling machine showing our new design;

FIG. 2 is a left side elevational view thereof;

FIG. 3 is a front elevational view thereof;

FIG. 4 is a rear elevational view thereof;

FIG. 5 is a bottom plan view thereof;

FIG. 6 is a top plan view thereof;

FIG. 7 is a right side elevational view of a combined cab and body for an earth-moving and handling machine showing a second embodiment of our new design;

FIG. 8 is a left side elevational view of the second embodiment;

FIG. 9 is a front elevational view of the second embodiment; and,

FIG. 10 is a rear elevational view of the second embodiment.

The bottom plan view and the top plan view of the second embodiment are identical to the bottom plan view and top plan view of the first embodiment.

The broken lines in the drawing are for illustrative purposes.
